(57) **CLAIM**

The ornamental design for a troffer assembly with U-shaped extensions, as shown and described.

DESCRIPTION

FIG. 1 is a perspective view of a troffer assembly with U-shaped extensions showing my new design;

FIG. 2 is a bottom plan view thereof;

FIG. 3 is a top plan view thereof;

FIG. 4 is a side view thereof. The opposite is a mirror image thereof;

FIG. 5 is a front elevation view thereof; and,

FIG. 6 is a rear elevation view thereof.

The broken lines illustrate portions of the device that form no part of the claimed design.
